WRIST PIN TOOL

Jack Caldwell, Havre, Mont.

Application December 1, 1939, Serial No. 307,155

1 Claim. (Cl. 29—88.2)

This invention relates to a wrist pin tool, and has for the primary object the provision of an efficient and inexpensive hand device of this character which will permit a person to easily and quickly place a wrist pin in a piston and connecting rod and to align the lock bolt opening of the wrist pin with the lock bolt opening of the piston and to thread the lock bolt into said openings with the device still in position within the wrist pin thereby saving a large amount of time in the application of the wrist pin in the piston and connecting rod.

With these and other objects in view, the invention consists in certain novel features of construction, combination and arrangement of parts to be hereinafter more fully described and claimed.

For a complete understanding of my invention, reference is to be had to the following description and accompanying drawings, in which

Figure 1 is a fragmentary vertical sectional view illustrating a portion of a piston and connecting rod having a wrist pin applied thereto through the use of the present invention.

Figure 2 is a view similar to Figure 1 showing the tool equipped with a sleeve for the purpose of adapting said tool to a wrist pin of a larger size than that shown in Figure 1.

Figure 3 is a vertical sectional view illustrating the tool.

Figure 4 is a perspective view illustrating the body of the tool.

Figure 5 is a perspective view illustrating an adjusting shaft of the tool.

Figure 6 is a perspective view illustrating one of the sleeves which may be provided for use in connection with this tool for adapting the latter to wrist pins of a larger size.

Figure 7 is a perspective view illustrating the centering pin.

Figure 8 is a transverse sectional view taken on the line 8—8 of Figure 3.

Figure 9 is a fragmentary sectional view showing the tool inserted in a portion of a piston with a wrist pin adapted thereto prior to aligning the opening of the wrist pin with the bolt opening of the piston.

Figure 10 is a detail elevational view showing a portion of a wrench applied to one end of the tool.

Referring in detail to the drawings, the numeral 5 indicates a fragmentary portion of a piston, 6 one of the wrist pin bearing portions of the piston and which is provided with a screw threaded locking bolt opening 7. 8 indicates a fragmentary portion of a connecting rod and 10 a 55

portion of a wrist pin, the latter having an opening which when properly applied to the piston and connecting rod must align with the opening 7 in order that the usual lock bolt may be threaded into the piston so as to extend into the piston pin for locking the latter in place in the bearing 6 of the piston. It is a very difficult matter to bring about the aligning of said openings without the aid of a special tool, otherwise considerable time is lost in the proper installing of a piston pin. To save time and render the application of wrist pins to pistons comparatively easy and quick the present invention may be employed.

An elongated cylindrical body 11 has one end portion provided with flattened faces 12 to be engaged by a wrench 13 or similar tool. The body 11 has a bore 14 extending from end to end thereof and arranged eccentrically of the axis of said body for the purpose of slidably receiving an adjusting shaft 15. The body 11 within its non-reduced end is provided with a screw threaded opening 16 to receive a set bolt 17. The body is further provided with an opening 18 which opens outwardly through one side of the body and communicates with the bore and the screw threaded opening to slidably receive an aligning pin 19, one end of which is beveled, as shown at 20. The pin 19 is further provided with a flattened face 21 defining at each end thereof shoulders 22. The set bolt 17 is adapted to engage the flattened face 21 of the aligning pin and prevents said aligning pin from turning in the opening 18 but which will permit the aligning pin to slide freely in the opening for a limited distance. The tapered end of the aligning pin enters the bore 14 of the body to ride against an inclined face or cam 23 formed in the adjusting shaft 15, the purpose of which is to bring about sliding movement of the aligning pin 19 in the opening 18 by endwise movement of the adjusting shaft 15 in the bore of the body.

The adjusting shaft extends a limited distance beyond one end of the body and is provided with a washer 24 held thereon by a cotter key 25. The washer 24 forms a seat for one end of an expansion coil spring 26, the other end of the spring bearing against one end of the body. The spring normally acts to position the shaft 15 so that the cam 23 will extend the aligning pin 19 to its fullest extent outwardly of the body 11 from one side of the body. A manual movement of the shaft 15 in one direction with respect to the body will position the cam 23 so that the aligning pin 19 may move fully within the opening 18 of the body which will permit a wrist pin

to be readily slid over the body and with the opening thereof brought into alignment with the opening 18. On freeing the shaft 15 the spring acts to drive the aligning pin through the opening of the wrist pin.

The adjusting shaft 15 is provided with a flattened face 27 to be engaged by a set screw 28 carried by the body 11 for the purpose of preventing the shaft 15 from rotating in the bore 14 of the body but which will permit the shaft 10 to slide relative to the body.

After a wrist pin of a conventional construction has been adapted to the body 11 as before described, the tool may then be used to insert the wrist pin through the bearings of the piston and connecting rod and by turning the body through the use of a wrench if necessary the aligning pin 19 may be brought opposite to the opening 7 of one of the bearings of the piston so that on alignment the pin 19 will enter the opening 7 of the piston properly aligning the opening of the wrist pin with said opening 7 so that a lock bolt may be threaded into the opening 7 and extend into the opening of the wrist pin. As the bolt is threaded into the opening 7 of the piston and the wrist pin the shaft 15 is moved endwise manually so that the aligning pin may slide under the influence of the set bolt and thereby be moved out of the openings of the piston and wrist pin. With the shaft thus held in the manually operative position the body may be withdrawn from the wrist pin thereby completing the job of applying the wrist pin and locking thereof into the piston.

As shown in Figure 2 and also in Figure 6, a sleeve 29 may be employed in conjunction with the body 11 when desiring to adapt this body to wrist pins of larger size. The sleeve is provided with an opening 30 through which the centering pin may pass for entrance into the opening of the wrist pin when the latter is adapt-

ed onto the sleeve 29. It is to be understood that this tool may be provided with several sleeves constructed similar to the sleeve 29 except having external diameters of different sizes 5 which consequently permits the use of the present invention with wrist pins ranging in different sizes as to their external and internal diameters.

It is believed that the foregoing description, when taken in connection with the drawings will fully set forth the construction and advantages of this invention to those skilled in the art to which such a device relates, so that further detailed description will not be required.

Having thus described the invention, what I claim is:

In a device of the character described, an elongated cylindrical body for insertion in a wrist pin and having an opening and a bore communicating with said opening, a centering pin operating in the opening, means for limiting the sliding movement of the centering pin and adapted to permit passing thereof through an opening of a wrist pin into a lock bolt opening 25 of a piston, a shaft slidable in the bore, a cam on said shaft to coact with the pin for imparting movement thereto by the sliding movement of the shaft, a spring acting on the shaft to impart movement thereto in one direction for the purpose of positioning the cam to extend the centering pin, and means for restraining the shaft against rotation in the bore permitting said shaft to slide in the bore, said centering pin having one end beveled to coact with the cam 30 of the shaft, and a sleeve adaptable to the body and having an opening to align with the opening of the body to permit the centering pin to extend therethrough and to permit the body to be adapted to a wrist pin of a larger size.

JACK CALDWELL.
